TELEVISION SYSTEM

Fritz Schröter, Berlin, Germany, assignor to Tele-funken Gesellschaft für Drahtlose Telegraphie m. b. H., Berlin, Germany, a corporation of Germany

Application August 7, 1937, Serial No. 157,818
In Germany August 29, 1936

5 Claims. (Cl. 178—6.8)

My invention relates broadly to the transmission of optical images and more particularly to a method of and apparatus for transmitting these images by television.

5 In the usual picture transmission method, more particularly in connection with television work, it is the absolute brightness or shading values of the constituent picture elements that are transmitted to a remote point even in cases 10 where they have not changed as compared with the values of the corresponding picture element in the transmission of the preceding frame in moving picture transmission. The fact that this means an unnecessary load on the transmission 15 channel, both from the view point of the intensity of the signals to be transmitted as well as also, possibly, from the viewpoint of the required frequency band should be appreciated.

Therefore, according to the present invention 20 the brightness or shading or density values of the picture elements are transmitted only to the extent where, contrasted with the corresponding and respective picture elements of the preceding frame, they have experienced an actual change.

25 But in accordance with the basic idea, namely, of transmitting only differences or different values, that is to say, to transmit to a distant point, as it were, only one picture which could be designated as a "difference picture," rather than the entire picture, there are conceivably quite a 30 number of different embodiments.

Among the latter there is an embodiment in 35 which transmission occurs at a velocity independent of the picture content and where, for instance, if the picture is dissected or scanned in straight parallel lines or strips, one works with a constant line and frame frequency. Among the methods of transmitting pictures at a velocity independent of the picture content may 40 be regarded to fall also a spiral scanning method wherein the velocity of the scanning pencil is constant or wherein the velocity inside the course or time of scanning each individual frame is subject to variation according to the same law.

45 A transmission to a remote point of a difference picture which proceeds at a rate of a velocity which, in the sense as hereinbefore outlined is independent of the picture content, offers the merit and advantage over the transmission method 50 involving always the absolute values of picture element brightness or shading as heretofore disclosed that the transmission channel, that is to say, for instance, an RF carrier wave will be called upon to carry smaller amplitudes and

that as a result interference of neighboring transmitters will be diminished.

But within the scope of the basic idea of the invention the differential picture could be transmitted also at a rate of speed which is dependent upon the comparative brightness values. This is feasible, for instance, by what is known in the art as velocity modulation. In this method, the scanning beam or pencil is so acted upon in reference to its speed that at the receiving 10 end, the intensity of the pencil re-creating and delineating the image may stay constant and stable, while, on the contrary, the speed of its migration or sweep over the area on which the incoming image is to be re-created will be so 15 much smaller the brighter any particular spot or element of the picture is to be re-created. If the differential picture is transmitted by this principle, then the scanning pencil or beam will have to sweep all those portions of the difference 20 picture at the sending end at a high rate of speed at which no change has occurred, while the delineating speed will be slower in the case of such picture elements where the difference picture or frame has a finite brightness or shading value. 25 However, inasmuch as the major part of the elements of a television image is altered from one frame to the next (imagining, for example, a scene in which a limited number of persons appear on a very variegated and detailed background) the transmission of the difference picture, for the same high definition, is accomplishable inside a briefer period of time than when using the method known in the earlier art in which again and again, the absolute shading 30 values of the picture elements were handled and transmitted rather than the differential values. However, fundamentally speaking this means that the width of the requisite transmission channel is reduced without this being associated with a 35 loss of picture detail as has heretofore been true. This progress could be utilized in practice either in the manner that for the transmission of the video signals a channel of reduced width is used or else that the picture so sent is made of higher 40 definition and richer in detail, in other words, by accommodating inside a given frame area a greater number of picture elements without the necessity of enlarging the corresponding transmission channel.

55 My invention will best be understood by reference to the drawings in which

Fig. 1 is an embodiment of my invention in which the differential picture is transmitted at a velocity independent of the picture content,

Fig. 2 is a receiving arrangement, and Fig. 3 is a schematic arrangement.

Referring to Fig. 1, 10 denotes a strip of film bearing frames 11 through 14. Anteriorly of the said film strip are two devices 15 and 16, say, two Braun type or cathode ray tubes which for each of the film frames 12 and 13 produce a spot designed to scan the two frames of the film in synchronism and in phase. Posteriorly of the film strip are mounted two photo-electric cells 17 and 18 which are provided with a common positive potential source of supply 19 and whose currents flow through two distinct resistances 20, 21. These resistances 20 and 21 in the manner as shown in the drawing are united with the control grids of two tubes 22 and 23, the grid circuits thereof including also the biasing voltage sources 24 and 25. The plate circuits of the two tubes contain the resistances 26 and 27 and distinct plate potential sources of supply 28, 29. Two cathode ray devices 30 and 31 have so-called storing surfaces 32 and 33, respectively are "unbroken" metal sheets (so-called mosaic elements) which latter are insulated from each other as well as from the joint co-operating coat so that in reference to this coat they represent tiny condensers. As to the rest, cathode ray devices 30 and 31, respectively, on the left-hand side of the surface 32 and 33 respectively, contains a secondary-emission anode 34 and 35 respectively, two deflection plate pairs 36 and 37, respectively, an anode 38 and 39 respectively, a cathode 40, 41, a control grid 42, 43, with which the beam or pencil issuing from the cathode 40, 41, respectively, may be subjected to a control action, and which is associated with the plate or tube 22 and 23, respectively. On the right-hand side of the storing surface 32 and 33, respectively, is a device known from the cathode ray picture scanning art and which, respectively, consists also of secondary emission anodes 44, 45, a pair of deflector plates 46, 47, anodes 48, 49, cathodes 50, 51, and also control grids 52, 53, respectively. Connected with the deflection plate pairs 36, 37 (which, however, could also be replaced by deflection coils) is a sawtooth wave generator 54 which furnishes deflection potentials for the two pairs of plates producing deflections in the two co-ordinate senses of the picture. From the storing surfaces 32 and 33 and the anodes 44 and 45, leads are brought respectively to amplifiers 55 and 56, both of which feed an RF transmitter 57. Also for the pairs of deflector plates 46, 47, which could also be replaced by deflector coils, there is provided a joint saw-tooth wave generator 58. The control grids 52, 53 of the two storing devices are connected with a device 59 consisting, for example, of a so-called multivibrator supplying positive and negative impulses of like duration and which furnishes the grids 52 and 53 alternately with a voltage designed to block out the cathode ray beam.

An arrangement of the kind shown in Fig. 1 operates in the manner that upon the two photoelectric cells 17 and 18 luminous fluxes corresponding to the absolute brightness or shading values of two congruous picture elements in the two frames 12 and 13 are made to impinge. Inasmuch as the drops of voltage across the resistances 20 and 21, which have a sense as indicated by the plus and minus signs, are connected in opposition with reference to the control grids in the two tubes 22 and 23, it will be seen that the potential of the control grid of tube 22 will be shifted in the positive sense only if the respective picture element of the film frame 13

happens to be darker than the corresponding picture point of the film frame 12. In this case the potential of the control grid of the tube 23 shifts into the negative region seeing that the fall of potential across the resistance 20 which furnishes for the tube 23 a negative grid voltage prevails over the fall of potential across the resistance 21 which represents a positive grid voltage for the tube 23. The size of the biasing potential sources of supply 24 and 25 to suit this scheme is to be chosen in such a way that, in the presence of the above assumptions, only tube 22 will conduct current, while tube 23 is blocked. But if, conversely, the picture element under consideration in film frame 13 is brighter than the respective picture element in frame 12, then the drop of potential across resistance 21 will surpass that across resistance 20 and tube 22 stays blocked, while tube 23 will conduct current. Now the cathode ray pencils issuing from cathodes 40 and 41, by the aid of control grids 42 and 43, respectively, will be acted upon and modulated in accordance with the differential values of the picture shading or brightness values, in other words, in accordance with the brightness of the differential picture in such a way that the elementary capacities of the storing surfaces 32 and 33 over which the modulated cathode-ray beam is swept by the aid of the pairs of deflector plates 36 and 37 will acquire charges which will correspond to the positive or the negative differential values, as the case may be. The cathode ray pencils issuing from the cathodes 50 and 51, by the aid of the deflection fields set up by the sawtooth wave generator 58 are sequentially swept over the storing surfaces 32 and 33. By virtue of the device 59 the beam scanning the storing surface 33 will be blocked out while the storing surface 32 is swept, and conversely, during the scanning of the storing surface 33 the cathode ray beam sweeping surface 32 will be blocked out. While these scanning actions are proceeding the RF transmitter 57 will be acted upon consecutively by the positive and the negative brightness values or intensities of the differential picture.

An exemplified embodiment of the receiver apparatus shall now be described by reference to Fig. 2. 60 denotes an RF amplifier with a power rectifier stage. The output resistance 61 of the said rectifier through lead 62 is united with the wiper of switch 63 to the contact steps of which busbars 64—66 are connected which correspond to the various lines of the picture re-creator or projection surface 67, while through lead 68 connection is established with two switch devices 69, 70 which are co-ordinated to the vertical rows of the picture re-creating means on picture surface 67. Two corresponding contacts of the said switches 69 and 70, say, contacts 71 and 72, are each connected through a tube 74, 74 shown only schematically with the busbars 75, 76 positioned perpendicularly in the picture projection surface 67, the outputs of the said two tubes having a high internal resistance being inter-connected. The picture re-creating means corresponding to the various picture points may consist, for instance, of small-sized cathode ray lamps 77 and 78 having a control grid, with a condenser such as 79 or 80, respectively, being interposed between the control grid and the cathode of each lamp. It will be understood that while mechanical switches 63, 69 and 70 have here been shown and described for the sake of simplicity of illustration, the more preferable scheme in practice will be to use instead cathode rays switch devices of suitable design.

The arrangement shown in Fig. 2 operates in the manner that while the switch arm or wiper 63 is positioned on busbar 64, and while the cathode ray beam scans, in the storing device 30 of Fig. 1, for instance, the positive differential values and then causes the same to be transmitted, the switch 69 of Fig. 2, transiently connects in sequence all cathode ray lamps which are connected with the busbar 64. Incidentally, the condensers 79, 80 of those cathode ray lamps will be further charged for which the respective picture elements exhibit an increase in brightness compared with the preceding frame, which means that positive values of the differential picture result in a charge of the condensers at the cathode ray lamps. After a given contact element of switch 69 has been abandoned, the charge upon the corresponding condenser is preserved so that the luminescent screen of the cathode ray lamp will be struck by a constant cathode ray current throughout the entire time interval until the recurrence of transmission of a possibly altered differential value for the picture element in question. After the positive differential values have thus been transmitted, a motion of the switch 70 will initiate transmission of the negative differential values in a similar manner. Suppose that while the scanning beam in the storing device 31 of the transmitter sweeps the storing surface, and when the contact 72 of switch 70 is contacted, a negative differential value, for example, is transmitted so that through the amplifier 74 a discharge of the condenser 79 will be brought about and that the other potential at the control grid of the cathode ray lamp 71 is reduced. After the contact step 72 has been abandoned, for the full interval of time until the transmission of the next differential value, the luminescent screen of this cathode ray lamp will be impinged upon by a constant cathode ray beam.

As already pointed out, particularly the switches 69 and 70, but optionally also the switch 63 could be of the cathode ray type it being recommendable in this connection to so dispose the contacts in the switch devices 69 and 70 that both switch pencils, by the agency of one and the same deflector field, may be moved in synchronism and in phase, such that the pencil in switch device 70 will reach its contacts only after the pencil in switch device 69 has already swept its contacts. This condition, in fact, has been indicated also in the case of the mechanical switches in Fig. 2 in that the angular path of both wipers comprise the same angle α , and that in the switch 69 the contact steps are disposed on the first half of the stroke, while in switch 70 they are arranged on the second half of the stroke. In a similar manner arrangements may be made so that also in the storing means 30, 31, the storing surfaces 32 and 33, respectively, will be scanned sequentially.

In connection with the question as to whether also switch 63 should be of the cathode ray pencil type or whether it should be of the mechanical type, the fact must be borne in mind that the frame frequency, if a differential picture according to this invention is transmitted, may be chosen far lower than in the picture transmission methods disclosed in the prior art. For the frame frequency need to be chosen only so high that the time brightness variations of the picture elements in the original are re-created with fair fidelity. These brightness fluctuations, however, are of a substantially lower frequency than the picture frequencies heretofore customary in tele-

vision work; hence, the speed of rotation of switch 63 will be fairly low.

Another chance to carry the basic idea of the invention into practice, as already pointed out above, is that the scanning of the storing surfaces 32, 33 at the sending end is effected by what has been called as the velocity modulation method. For this purpose, the arrangement shown in Fig. 1 need to be altered but little, as illustrated in Fig. 3. The amplifiers 55, 56, which furnish the positive and the negative brightness or intensity values of the differential picture in a way as known from the velocity modulation method, act upon the sawtooth wave generators 58', 58''; the potentials produced by them are applied, on the one hand, upon the deflector plate pairs 46, 47, while, on the other hand, they are fed to the transmitter 57. The scanning pencils, as previously stated, rapidly sweep over those portions of the storing surfaces 32, 33 where the differential picture has no finite amplitude, whereas a slower scanning takes place only where the differential picture exhibits contrast of detail. In this manner a reduction in the requisite frequency band as above stated is realized, for it will be understood that at all points along a line where the differential picture is of zero amplitude the scanning beam will slip over quickly so that no appreciable time for transmission is required.

In case the velocity modulation method is employed at the sending end, the receiver apparatus may be built fundamentally similarly as described by reference to Fig. 2. All that is required is that the switch arms or wipers of switch devices 69 and 70 must be caused to revolve at a rate of speed that will vary in accordance with the velocity modulation or scanning used at the sending end, rather than rotating the same at a constant rate of speed. Switch 63 which should in this case be preferably of the cathode ray type just like switch devices 69 and 70 must be changed over to the horizontal busbar 64—66 next following after a whole picture strip has been completely scanned. This, as known in the prior art, is readily accomplishable by the aid of a distinct contact 81 at the end of the contact row or bank in the switch 70.

As can be inferred from what precedes, re-creator means have been assumed to exist at the receiving end according to the present invention for the various picture elements which, after having been once excited, exhibit a constant after-effect. In the exemplified embodiment as shown in Fig. 2 this is produced by that the condenser coats 79, 80, retain their charges set up or supplemented through the amplifiers 73, 74. In order to compensate for such gradual leaking away of these charges as may happen across the insulation resistance of these condensers, and in order to effect originally the adjustment of the picture, one may proceed in such a way that, from time to time, the frame 12 of the film strip is completely masked at the sending end, while over the picture field of frame 13 a shutter is made to travel which will expose, for instance, only a few lines of the latter picture field. Thus the absolute values of the picture point brightness or shading of the latter picture section (which, because of the complete masking of the film frame 12 are the same as the differential values) will be transmitted and be re-created at the receiving end. Thereafter, for a comparatively long period of time, only the differential values in the brightness distribution of the picture can

be transmitted, provided that there occurs no complete change of scene in the picture to be transmitted to a distant point. While the major portion of the television picture is transmitted only in so far as the differential values compared with the preceding frame is concerned, it would also be feasible to transmit for a few picture lines always the absolute values of the picture element brightness and to change periodically the position of these picture lines. With this end in view, a few picture lines or strips inside the picture field of frame 12 would have to be completely masked so that inside the picture field of frame 13 the absolute values rather than the differential values of the picture element brightness in the masked lines would be televised.

What I claim is:

1. A system for transmitting optical images by television comprising a transmitter for sequentially transmitting a differential value of simultaneously developed picture signals representing corresponding elemental areas on at least two complete picture representations, a receiver wherein each picture point representation may be pre-set to an optical value representative of the optical value of the transmitted picture for one frame thereof, and means for sequentially changing the optical values at the receiver in accordance with the transmitted differential representation.

2. A television system comprising a transmitter, said transmitter including means for sequentially developing a differential representation of the optical values of each elemental area of at least two complete optical representations to be transmitted, said differential quantity being developed from substantially simultaneously developed picture signals, receiver means comprising a plurality of individual picture point reconstructing means, means for pre-setting said picture point

representing means to represent definite optical valuations, and means for sequentially changing said picture point representations in accordance with the transmitted differential representation from said transmitter.

3. Apparatus in accordance with claim 2 wherein said receiver means comprises a plurality of individual light reproducing elements representative of the picture points of the optical image, means for pre-setting said picture point representations to a predetermined value, and means for maintaining said picture point representing means at said predetermined value for a predetermined length of time, and means for sequentially changing the operating level of said picture point reproducing means in accordance with the transmitted differential representation.

4. Apparatus in accordance with claim 2 wherein said receiver means comprises a plurality of light sources each representative of the picture point of the optical image to be reproduced, a vacuum tube means having each of said picture point reproducing means in the output circuit thereof, condenser means connected in the input circuit of each of said vacuum tubes for maintaining the tube at a predetermined operating level, and commutating means adapted to energize said condenser means and to control the charge on said condenser means in accordance with the transmitted differential representations.

5. Method of television comprising the steps of simultaneously examining at least two frames of the image to be transmitted, developing a differential representation of each of the corresponding optical points on both of said frames, transmitting said developed representations, and controlling the optical image reproduction in accordance with the developed differential representations.

FRITZ SCHRÖTER. 40
